UNITED STATES PATENT OFFICE.

GUY H. PRESTON, OF DOUGLAS, ARIZONA.

MESS KIT.

1,383,853.

Specification of Letters Patent.

Patented July 5, 1921.

Application filed November 10, 1919. Serial No. 336,975.

To all whom it may concern:

Be it known that I, GUY H. PRESTON, a citizen of the United States, stationed at Douglas, in the county of Cochise and State 5 of Arizona, have invented certain new and useful Improvements in Mess Kits; and I do hereby declare the following to be a full, clear, and exact description of the invention, such as will enable others skilled in 10 the art to which it appertains to make and use the same.

My present invention relates to improvements in mess kits for use by soldiers, miners, prospectors, or others having need 15 of a canteen and mess articles which may be put up in a compact package and conveniently transported either on the person of an infantryman, or attached to the saddle of a trooper, or carried by a miner or prospector 20 in any convenient way.

My present invention relates more especially to providing a canteen of an annular shape having a central recess of cylindrical or tapered form adapted to receive a cup or 25 other cooking or drinking vessel, having a handle adapted to be sprung over the edge of the canteen and attaching thereto one or 30 more plates, preferably two, nested, fitting snugly about one side of the canteen, leaving the other side open to receive the cup referred to. The side of the canteen opposite the plates is preferably made substantially flat so that the knife, fork and spoon comprising the balance of the mess kit may 35 be conveniently held thereon in a compact way; but these, as well as the casing, are not necessarily a part of the invention which comprises the provision of a canteen with a cup and plates of normal construction and 40 use, such as are commonly used by civilians and others. In other words, the idea of the present invention is more especially to provide a canteen which may be conveniently used in connection with cups and plates of 45 standard size and shape, rather than to manufacture the cups and plates to fit the canteen.

My invention is especially intended to provide a simplified and improved form of 50 device over that shown in my earlier patents dated and numbered respectively, 555,582, March 3, 1896, and 911,442, February 2, 1909, and both entitled Improvements in field ration mess kits.

My invention will be more fully understood after reference to the accompanying

drawings, in which like parts are indicated by similar reference symbols throughout the several views, and in which:

Figure 1 shows a section through the canteen, the cup and the nested plates, the parts being shown in the assembled position, and the cover of the canteen as well as the knife, fork and spoon being omitted as not a part of my present invention.

Fig. 2 is a perspective view showing the canteen without the cup and plates.

Fig. 3 is a perspective view of a cylindrical cup adapted to be used with the canteen, of the form shown in Figs. 1 and 2.

Figs. 4 and 5 are perspective views of the two plates which may be nested and attached to the side of the canteen, as shown in Fig. 1; and

Fig. 6 is a sectional elevation of a modified form of canteen and cup, in which the opening in the center of the canteen and the cup are shown as tapered, in the form of a frustum of a cone; while the two plates are shown of unequal depth, it being often 80 desirable to have one plate deeper than the other for reasons that will be hereinafter described.

Referring first to Figs. 1 to 5, A represents the canteen proper provided with an 85 opening A^o having cylindrical walls, and with a neck a covered by the screw cap A'.

The periphery of the canteen is preferably of cylindrical form, as shown at a', and one side of the canteen is preferably 90 nearly flat, as shown at a^o, and the other side is shaped, as at a², to fit snugly into tin plates of the ordinary commercial make, so that the same may be nested thereon, as will be hereinafter described.

The cup B is shown in Figs. 1 and 2 as of cylindrical form, and provided with the usual bead b, and with the handle B' which has the downwardly projecting resilient arm b' provided with the bead b². This resilient 100 arm is adapted to spring against the cylindrical portion a' of the periphery of the canteen, and normally holds the cup against shaking loose on the canteen, and is also out of the way. This handle is connected 105 to the cup in any convenient way, as by the rivets b³, and the body portion of the cup fits snugly in the central recess A^o in the canteen.

Attached to the side a² of the canteen are 110 one or more plates C, C' of standard pattern, each preferably having the bead c.

These plates may be nested as shown in Fig. 1.

In Fig. 6 I have shown a similar arrangement to that shown in Figs. 1 to 5, except that the body of the cup B² is tapered and fits in the tapered central opening in the canteen; and of the two plates C and C², nested as shown, the outer plate is preferably of less depth than the inner.

10 It has been found in practice in the field that it is desirable to have a plate deep enough to hold liquids or semi-liquids, such as stew, soup, or the like, while a shallower plate may be more conveniently used for 15 meats, bread or solid materials.

It will be obvious that with the form of cup shown in Fig. 6 two or more cups may be nested, just as the plates are nested, and the two or more cup handles may project 20 laterally and fit over the edge of the canteen, just as is shown in Figs. 1 and 6, or the inner cups of the nest need not be provided with handles if preferred.

The central cup when in the assembled position, as shown in Figs. 1 and 6, affords a convenient receptacle in which to stow food or other articles that may be needed, and the whole constitutes a compact package in which the cup and the handle attached 30 thereto are compactly and conveniently attached to the canteen, and do not require as much additional space as when carried separately; and in which the cup is protected from injury by the canteen, and the canteen 35 itself is more or less stiffened and strengthened by the cup and its handle.

It will be noted that in the construction of the several parts herein described, to wit: the canteen, the cup and the plates, the 40 circular or cylindrical form is adhered to, and there are no sharp angles. This is especially desirable owing not only to facility and economy in manufacture, but also to provide strength in the various parts and to 45 prevent there being any sharp angles or corners in which dirt or other foreign matter tends to accumulate, which, when used in articles of this kind, are very apt to render the same unsanitary.

50 Basically, the development of the idea consists in devising two nested plates of normal and familiar shape, placing in the center of the upper plate a cup, also of normal and familiar shape, and then conforming a 55 canteen to occupy the annular space outside the cup and within the upper plate, and forming this canteen with a substantially flat top and with a filling opening on the side, thus the flat top affording a convenient 60 stowage place on which the knife, fork and spoon forming the balance of the kit may be placed.

In other words, primarily, the cup and plates are first devised and the canteen is 65 made to conform thereto, thereby giving to

the cup and plates the configuration of maximum utility, independently of the form of the canteen.

By providing a handle to the cup of the shape shown, this handle is practically out 70 of the way and adds practically nothing to the bulk of the package, and yet enables the cup to be conveniently handled. A handle is indispensable in a cup forming part of a military mess kit, and the handles of the 75 ordinary shape as applied to metal cups are apt to be in the way, or too short, or take up too much room.

By having the opening A⁰ extending entirely through the canteen the metal cut out 80 of both sides of the canteen is saved, while the circular wall around said openings provides a rigid stiffening member which protects the canteen against most of the 85 injuries incident to the rough usage to which such articles are inevitably subjected.

It will be noted that the cup when in the assembled position will also serve as a stiffening member to the canteen and will in a measure protect the circular walls of the 90 opening A⁰ from injury.

While I have included two embodiments of the invention in the form believed by me to be best suited to the purposes for which the invention is designed, it will be obvious 95 that changes in the details of construction, and in the combination and arrangement of parts may be made which could be used without departing from the spirit of my invention; and I do not mean to limit the invention to such details except as particularly pointed out in the claims.

Having thus described my invention what I claim and desire to secure by Letters Patent of the United States is:—

1. A mess kit comprising an annular canteen provided with a central perforation having substantially cylindrical walls, a curved bottom adapted to fit a metal pan of standard shape, a substantially cylindrical outer wall, and a substantially flat top, with a neck projecting from said cylindrical portion, and a cap normally closing said neck, with a substantially cylindrical cup adapted to fit snugly in said central portion, and provided with a resilient handle adapted to lie radially on and to fit snugly against said top, the said handle having a downwardly projecting laterally curved arm adapted to be sprung over and engage the cylindrical outer wall of the canteen and to hold said cup against accidental displacement when the parts are assembled, substantially as described.

2. A mess kit comprising an annular canteen provided with a central perforation having substantially cylindrical walls, a curved bottom adapted to fit a metal pan of standard shape, a substantially cylindrical outer wall, and a substantially flat top, with

a neck projecting from said cylindrical portion, and a cap normally closing said neck, with a substantially cylindrical cup adapted to fit snugly in said central portion, and
5 provided with a resilient handle adapted to lie radially on and to fit snugly against said top, the said handle having a downwardly projecting laterally curved arm adapted to

be sprung over and engage the cylindrical outer wall of the canteen and to hold said cup against accidental displacement when the parts are assembled, with a pair of pans nested together and fitting snugly over the bottom of the annular canteen, substantially as described.

GUY H. PRESTON.
